UNITED STATES PATENT OFFICE.

JOHN DESMOND, OF BRIDGEPORT, CONNECTICUT, ASSIGNOR TO THE HAYDEN & DERBY MANUFACTURING COMPANY, OF NEW YORK, N. Y.

STEAM-INJECTOR.

SPECIFICATION forming part of Letters Patent No. 464,339, dated December 1, 1891.

Application filed July 1, 1891. Serial No. 398,099. (Model.)

To all whom it may concern:

Be it known that I, JOHN DESMOND, a citizen of the United States of America, residing at Bridgeport, in the county of Fairfield and 5 State of Connecticut, have invented certain new and useful Improvements in Steam-Injectors, of which the following is a specification, reference being had therein to the accompanying drawings.

10 This invention pertains to certain improvements in steam-injectors, having for its object the production of an injector wherein the lifting qualities are regulated by adjusting the suction-tube and in which all the tubes 15 may be controlled by a single valve-stem or other operating device at the discharge end of the injector.

The invention consists in a steam-injector having a water-chamber at one end, into which 20 the steam-inlet and suction tubes open, said suction-tube being adjustable with relation to said steam-inlet tube, the operating rod or stem for adjusting said suction-tube being extended through the delivery end of the injector and having its inward and outward 25 movements limited by a stop located adjacent to its inner end.

The invention further comprises the detail construction, combination, and arrangement 30 of parts, substantially as hereinafter fully set forth, and particularly pointed out in the claims.

In the accompanying drawings, Figure 1 is a vertical longitudinal sectional view of an 35 injector constructed in accordance with my invention. Fig. 2 is a horizontal sectional view on the line $x-x$, Fig. 1. Fig. 3 is a similar view on the line $y-y$, same figure.

Referring to the drawings, A designates the 40 casing; a, the steam-inlet port; a', the water-inlet port; a², the delivery-port, and a³ the overflow arm or branch, which is arranged at one side of the injector about midway between the water-inlet port a' and the delivery-port a². The overflow arm or branch a³ 45 has an inclosing casing a⁴, the lower end of which is open, and into its upper end is screwed a plug a⁵, through which is passed the stem of a valve a⁶. This valve is designed to 50 be seated upon the outer open end of the overflow-arm a³.

B is the water-chamber, located in the upper end of casing a, the same being formed by the end wall b and an apertured diaphragm b', the latter being about coincident with or 55 just beneath the lower portion of the water-inlet port a'. Adjacent to water-chamber B is overflow-chamber b², from which opens the overflow arm or branch a³, and next to this is delivery-chamber b³, a circular flange b⁴ separating said chambers b² b³ from each other. 60

C is the steam-inlet tube, which is preferably screwed into the threaded aperture in the end wall b, and its inner end projects to about midway of water-chamber B. This 65 steam-inlet tube opens directly into the water-chamber, no steam-chamber being employed.

D is the suction-tube, which is adjustable with relation to the steam-inlet tube C. The 70 upper portion of this tube is projected through the aperture in diaphragm b', and at its lower end said tube is provided with a chamber or enlargement d'. Within this chamber or enlargement d' is a threaded ring 75 d², held by lateral arms d³ integral therewith and with said chamber d'. Into this threaded ring is screwed the upper end of combining-tube E, with which is formed the delivery-tube F, a slot or overflow-port e marking the point 80 of connection between said tubes. A second slot or overflow-port e' is formed in the combining-tube. Upon this tube is a cylindrical or rounded portion e², terminating at its lower end in a flange e³, and upon delivery-tube F 85 is a corresponding cylindrical portion f and an upper flange f'.

G is an auxiliary check-valve designed to move on the cylindrical portion e² of combining-tube E and rest upon flange e³ or bear 90 against the lower open end of chamber d' of suction-tube D. This valve is provided with upper and lower curved surfaces, as shown, so as to form a peripheral flange g and insure a better or firmer seat for the valve against 95 chamber d'.

H is a flanged washer, through a central aperture of which the delivery-tube F is passed. This washer is firmly held in place against flange b⁴ by the inner end of a cylindrical extension i, projecting from an end plug i', 100 screwed into the lower end of casing a. A

series of holes or apertures i^2 is formed in extension i , through which the steam and water escape from the delivery-chamber on the way to the boiler. The upper surface of washer H acts as a seat for flange f of the delivery-tube, while against its lower surface may be seated the circular end or ring i^3 of a rod or stem I , said ring being supported by arms i^4 of said rod or stem. Thus the washer 5 serves as a stop to limit the inward and outward movements of the series of tubes and the rod or stem. This rod or stem is provided with a thread i^5 , which engages a corresponding thread in the end plug. The ring 10 i^3 of this stem is screwed onto the delivery-tube, whereby by operating the handle i^6 of said stem all the tubes can be moved simultaneously, the movement of the delivery-tube being limited by the washer H . The same results 15 can be secured by dispensing with the lower flange f on the delivery-tube, which latter must fit flush in the aperture of the washer.

By removing the end plug all the tubes, save 20 the steam-inlet tube, can be at once withdrawn from the injector. By turning the valve-stem I the suction-tube can be moved away from or toward the steam-inlet tube. In its upper position the suction-tube regulates 25 the amount of water necessary to work the injector on low-steam pressure—say about twenty pounds—and the extreme lower position of said tube enables the injector to work on high steam-pressure—say up to two 30 hundred pounds. In this way I am enabled to secure a high or low pressure injector, the turning of a single rod or stem resulting in securing the desired regulation. The upper position of the suction-tube is regulated by 35 the circular end of rod or stem I bearing against washer H , while when in its lower position flange f of the delivery-tube is seated against said washer.

The operation of my improved injector is 40 as follows: Steam being admitted through the steam-inlet tube and the handled rod or stem turned the desired extent, opening up the space between the steam-inlet tube and the suction-tube, water will be drawn into 45 the water-chamber, and upon passing through the suction-tube will fly into the overflow-chamber, and escaping through the overflow arm or branch will, upon opening the valve of the latter, create a vacuum in the casing 50 and effect the closing of the auxiliary check-valve G against the lower end of the suction-tube, thus cutting off the escape of steam and water at that point. The column of steam 55 and water being established, the same will travel through the combining and delivery tubes and pass onto the boiler, and a vacuum 60 being created in the overflow arm or branch the overflow-valve is at once seated.

I do not restrict myself to the construction 65 and arrangement of the suction, combining, and delivery tubes, as above specified, since the main object of my invention is to regu-

late the working of the injector so as to secure a high and low pressure injector by controlling the supply of water through the adjustment of the suction-tube by means extended beyond the delivery end of the injector. Therefore this latter tube can be connected and operated in any desired manner. It will also be understood that I do not restrict myself to the means shown and described for effecting an adjustment of the tubes, since other suitable or preferred means can be employed with equally good results.

I claim as my invention—

1. The herein-described improved steam-injector, having the water-chamber at one end, into which the steam-inlet tube opens, the suction-tube opening into said water-chamber and adjustable with relation to said steam-inlet tube, the operating rod or stem for adjusting said suction-tube, extended through the delivery end of the injector, and a stop adjacent to the inner end of said rod or stem for limiting the inward and outward movements thereof, substantially as set forth.

2. The herein-described improved steam-injector, having the water-chamber at one end, the steam-inlet tube opening thereinto, the suction-tube, the combining-tube connected thereto, the delivery-tube connected to said combining-tube, the rod or stem connected to said delivery-tube and extended through the delivery end of the injector, and the washer located between the delivery-tube and the rod or stem, forming stops for limiting the inward and outward movements of said rod or stem and of said series of tubes, substantially as set forth.

3. The herein-described improved steam-injector, comprising the suction-tube having a cylindrical chamber, a threaded ring therein, the combining-tube engaging said ring and having a cylindrical portion and a flange, and an auxiliary check-valve on said cylindrical portion beneath or to one side of said cylindrical chamber, substantially as set forth.

4. The herein-described improved steam-injector, comprising the casing having the overflow-chamber and a flange at the lower end thereof, the suction-tube, the combining-tube secured thereto, the delivery-tube projecting from said combining-tube, the washer through which said delivery-tube is projected, the end plug having a cylindrical portion bearing against said washer, and the rod or stem secured to said delivery-tube and working in said end plug, substantially as set forth.

5. The herein-described improved steam-injector, comprising the casing having the water-chamber at one end, the steam-inlet tube opening thereinto, the suction, combining, and delivery tubes connected together, the rod or stem connected to said latter tube, and the removable end plug through which said rod or stem is passed, substantially as set forth.

6. The herein-described improved steam-

injector, comprising the casing having the water, overflow, and delivery chambers, the steam-inlet port at its upper end, the water-inlet port opening into said water-chamber, the delivery-port coincident with said delivery-chamber, the steam-inlet tube opening into said water-chamber, the suction, combining, and delivery-tubes connected together, the rod or stem connected to said delivery-

5 tube, and the end plug through which said rod or stem is passed, substantially as set forth.

In testimony whereof I affix my signature in presence of two witnesses.

JOHN DESMOND.
